ATTORNEY

UNITED STATES PATENT OFFICE.

JOHN DANNER, OF CANTON, OHIO.

DESIGN FOR A BOOK-RACK.

SPECIFICATION forming part of Design No. 20,074, dated August 5, 1890.

Application filed June 25, 1890. Serial No. 356,723. Term of patent 7 years.

To all whom it may concern:

Be it known that I, JOHN DANNER, a citizen of the United States, and a resident of Canton, county of Stark, State of Ohio, have 5 invented a new and useful Improvement in Designs for Book-Shelves, of which the following is a full, clear, and exact description, reference being had to the accompanying drawing, making part of this specification.

10 My invention relates to a design in book-racks.

The drawing illustrates a perspective of my design for book-racks.

15 The case A is a parallelogram in form of a series of shelves B placed in vertical order, spaced apart, and supported at the four corners by posts C, said posts having a turned foot or bottom portion a, a square portion b, turned spacing portion c, of irregular form,

and an oval top portion d. The posts are secured to the corners of the shelves B, as shown, and supported thereby. At the end portions of the shelves is provided a series of corresponding perforations k, in which is placed a corresponding series of rods m, the lower ends of said rods resting in the perforations in the lower shelf, the upper ends projected a distance above the upper shelf.

What I claim as new, and desire to secure by Letters Patent, is—

20 The design for a book-rack, as herein shown and set forth.

In testimony whereof I have hereunto set my hand this 13th day of June, A. D. 1890.

JOHN DANNER.
